VALVE HOLDER AND LIFTER

Filed May 7, 1930

Joe Eagan,

INVENTOR

BY *Victor J. Evans*

ATTORNEY

P. J. Evans

WITNESS:

UNITED STATES PATENT OFFICE

JOE EAGAN, OF HILLSBORO, TEXAS, ASSIGNOR OF ONE-HALF TO OLEN E. BASS, OF BYNUM, TEXAS

VALVE HOLDER AND LIFTER

Application filed May 7, 1930. Serial No. 450,555.

This invention relates to means for holding valves in the head of a motor while the springs of the valves are being depressed, and to means for depressing the springs, the 5 general object of the invention being to provide means whereby all the valves in a head can be held against movement while the springs are being depressed so that it is not necessary to frequently turn the head and 10 to provide adjustable means for depressing the springs while they are held by the first mentioned means.

A further object of the invention is to make the holding device collapsible so that 15 it will occupy but little space when placed in a tool box or other place.

This invention also consists in certain other features of construction and in the combination and arrangement of the several parts, to 20 be hereinafter fully described, illustrated in the accompanying drawings and specifically pointed out in the appended claims.

In describing the invention in detail, reference will be had to the accompanying drawings 25 wherein like characters denote like or corresponding parts throughout the several views, and in which:—

Figure 1 is a bottom plan view of a head of a motor, showing the holding means in use.

30 Figure 2 is a section on line 2—2 of Figure 1, with the valve contracting means in use.

Figure 3 is a view of the holding device in collapsed condition.

In these views, the letter A indicates a bar 35 formed of the sections 1 and 2 which are hingedly connected together by a clip 3 to which the adjacent ends of the sections are pivoted. A slot 4 is formed in each section and a bolt 5 passes through each slot and is adapted to be passed through one of the bolt 40 holes in the head B of the motor so that when the nut 6 on the bolt is tightened, the section will be clamped to the under face of the head, as shown in Figures 1 and 2. Each section 45 has a number of arms 7 pivoted thereto and a link 8 is pivoted to the outer end of each arm. A disk 9 is pivoted to the outer end of each link, each disk being adapted to engage a pair of the valves C of the head. Thus by 50 clamping the member A to the under face of

the head by the bolts 5 and adjusting the arms 7 and their links 8 to place the disks in engagement with the valves, the valves are held upon their seats so that the springs can be contracted to enable the pins 10 to be removed from or replaced in the stems. 55

The spring manipulating means consists of a lever 11 having a hole at one end for receiving a threaded member 12 which carries the nuts 13, a nut being located on each side of the lever so that by adjusting the nuts, the member 12 can be adjusted in the lever. A hook 14 is pivoted to the member 12 and is adapted to engage the rocker arm shaft 15. A bar 16 is pivoted to the lever 60 an appreciable distance from the member 12 and is formed with a shoe 17 for engaging the spring seat 18 of the valve. Thus by placing the hook 14 in engagement with the shaft 15 and placing the shoe on the spring seat, the lever would be depressed so as to cause the member 16 to depress the spring 65 so that the pin 10 can be removed or replaced. 70

The holders will adjust themselves to any 75 size motor and when not in use, the device can be folded, as shown in Figure 3, so that it can be placed in a tool box or any other place. As before stated, the valve holding device will hold all the valves in position 80 and it is not necessary to turn the head over every time a key is removed or replaced.

It is thought from the foregoing description 85 that the advantages and novel features of the invention will be readily apparent.

It is to be understood that changes may be made in the construction and in the combination and arrangement of the several parts, provided that such changes fall within the scope of the appended claims. 90

What I claim is:—

1. A device of the class described comprising an elongated sectional foldable member, a plurality of swinging arms pivotally connected therewith, a link pivotally connected with each arm, a valve engaging disk pivoted to each link and means for adjustably and detachably clamping the member in place on the head of a motor. 95

2. A device of the class described com- 100

prising an elongated member, a plurality of arms pivotally connected therewith, a link pivotally connected with each arm and a valve engaging disk pivoted to each link, said member being formed of two parts hingedly connected together, each part having an elongated slot therein and bolts passing through the slots and adapted to pass through some of the bolt holes of a head of a motor.

In testimony whereof I affix my signature.
JOE EAGAN.
